US00D607462S

(12) **United States Design Patent**
Chen

(10) **Patent No.:** **US D607,462 S**
(45) **Date of Patent:** **** Jan. 5, 2010**

(54) **PORTABLE STORAGE DEVICE**

(75) Inventor: **Chu-Chou Chen**, Taipei (TW)

(73) Assignee: **A-Data Technology (Suzhou) Co, Ltd.**
(CN)

(**) Term: **14 Years**

(21) Appl. No.: **29/332,530**

(22) Filed: **Feb. 18, 2009**

(30) **Foreign Application Priority Data**

Aug. 25, 2008 (CN) 2008 3 0184525

(51) **LOC (9) Cl.** **14-99**

(52) **U.S. Cl.** **D14/480.5**

(57) **CLAIM**

The ornamental design for a portable storage device, as shown and described.

DESCRIPTION

FIG. 1 is a perspective view of a portable storage device showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 4 Drawing Sheets

FIG. 1

FIG. 2

FIG. 3

FIG. 4

FIG. 5

FIG. 6

FIG. 7
